UNITED STATES PATENT OFFICE

LEO SCHILDKNECHT, OF ST. LOUIS, MISSOURI, ASSIGNOR TO LANDIS MACHINE COMPANY, OF ST. LOUIS, MISSOURI, A CORPORATION OF MISSOURI

HEEL-TAP TRIMMER

Application filed November 28, 1927. Serial No. 236,288.

My invention relates to shoe working machinery, particularly to a heel tap trimming device, especially adapted for use in shoe repair shops.

5 The main object of my invention is to protect the body of a shoe heel from being marred when the tap is applied thereto and is trimmed flush with the surface of the heel.

It is customary in shoe repairing to apply 10 taps which are somewhat larger in area than the bottom of the heel and then to trim the surplus material from the edge of the tap, making the edge of the latter form a continuation of the heel surface. Heretofore, 15 the cutter used for this purpose has had its face covered by a collar which served to retain the cutter on its shaft and also served to prevent cutting of the body of the heel by the cutter. Since the cutter and collar rotate 20 at high speeds, contact of the collar with the body of the heel would frequently result in injury to the heel finish, even though the peripheral edge of the collar would be fairly smooth. I attain by general object by the 25 provision of a stationary guard adjacent the edge of the cutter.

I also desire to provide a stationary guard which may be adjusted relative to the cutter and which may be moved away from the cutter 30 when it is desired to replace the cutter.

In the accompanying drawings which illustrate a selected embodiment of my invention—

Figure 1 is a front elevation of a tap trimming cutter, the shaft on which it is mounted, a bearing for the shaft, a gauge, and my present new guard.

Figure 2 is an end elevation of the same parts.

40 Figure 3 is a top view of the same parts.

Figure 4 is a detail section taken on the line 4—4 of Figure 1.

The operating shaft is indicated at 1, and is journaled in a suitable bearing 2 which 45 may be applied to or form a part of the frame of the machine. A cutter 3, of familiar form, is mounted on the end of shaft 1, being secured in place by a collar 4 and a screw 5 which is inserted in the end of the shaft 1.

50 A gauge 6 is slidably mounted on shaft 1 and

may be retained in desired position thereon by means of screw 7.

Mounted on bearing 2 is a two-part bracket 8—9 secured together by means of a wing nut 10. The upright leg 11 of bracket element 9 mounts my stationary guard which preferably consists of a vertical arm 12 and an annular guard portion 13, adapted to be positioned adjacent to the edge of the cutter 3. Sufficient play will be provided between 60 screws 14 and the openings therefor in arm 12 so that the latter may be moved up and down, or back and forth, to secure the proper adjustment of the guard relative to the cutter whereupon screws 14 may be tightened to 65 frictionally retain the guard in position. A set screw 15 provided with a lock nut 16 is mounted on a lug 17 formed on bracket element 9 and forms a stop for the guard so that pressure against the edge of the guard 70 will be positively resisted. The screw and slot assembly of the bracket elements 8 and 9 permit the guard to be adjusted axially of the cutter and its shaft.

Figure 3 illustrates the application of a 75 heel to the cutter, the body of the heel H resting against guard 13 and the tap bearing against the forward face of gauge 6 and having its edge in contact with the teeth of the cutter 3. It will be seen that there is no 80 moving part adjacent the heel body which can injure the latter. The guard provides a support for the heel, thereby enabling the workmen to trim the tap more accurately than has been the case heretofore, when it 85 was necessary for the workmen to maintain a space between the heel and the rotating collar previously used which extended to the periphery of the cutter.

Obviously the details of the structure described may be varied without departing from the spirit of my invention, and I contemplate the exclusive use of such modifications as come within the scope of my claims.

I claim:

1. In a device for trimming the tap of a heel on a shoe, a rotatable cutter, a cylindrical member having a smooth end projecting over the teeth of said cutter and adapted to engage the face of the heel tap to determine 100

the width of a cut made by said cutter on the edge of the heel tap, and a guard mounted in spaced relation to said member and adjacent to the teeth of said cutter and adapted 5 to engage and protect the body of the heel to which the tap is applied, said guard being flat across the axis of the cutter and free from projections extending a substantial distance away from said cutter whereby the shoe 10 shank may be projected across said axis to trim the breast of the heel tap.

2. In a device for trimming the tap of a heel on a shoe, a rotatable cutter, a gauge overlying the teeth of said cutter and having 15 a smooth edge for engaging the face of a tap on a heel on a shoe, and a stationary member spaced from said gauge surface and including a guard adjacent to the teeth of said cutter for engaging the body of the heel 20 to which the tap is applied, said guard terminating substantially at the edge of the cutter teeth and being relatively thin and flat across the axis of the cutter and free from projections extending from the cutter which would 25 interfere with the presentation of the breast of the heel tap to the cutter.

3. In a device for trimming the tap of a heel on a shoe, a journal bearing, a shaft projecting through said bearing, a cutter mounted 30 on said shaft, a bracket mounted on said bearing and extending parallel with said shaft and terminating abreast of the outer end of said cutter, and a straight relatively flat guard member secured to the outer end 35 of said bracket and projecting across the axis of said cutter with its edges aligned with the teeth of said cutter whereby a shoe shank may be projected across said axis when the breast of the heel tap is being trimmed.

40 4. In a device for trimming the tap of a heel on a shoe, a rotatable cutter, a guard for the side of the shoe heel comprising a relatively thin flat element with its outer edge adjacent to and substantially aligned with 45 the edge of the cutter teeth, a support arm for said guard lying in substantially the same plane with a portion projecting inwardly over said cutter, and means for mounting said portion.

50 5. In a device for trimming the tap of a heel on a shoe, a journal bearing, a shaft projecting through said bearing, a cutter mounted on said shaft, a cylindrical edge gauge mounted on said shaft and adjustable longitudinally thereof and surrounding the inner 55 ends of the cutter teeth, a bracket secured to said bearing and projecting over said gauge and cutter, and a guard for the side of the shoe heel comprising a flat bar secured to said bracket and extending therefrom in a plane across the outer end of said cutter with its edge adjacent to the edge of the cutter teeth.

6. In a device for trimming the tap of a 65 heel on a shoe, a journal bearing, a shaft pro-

jecting through said bearing, a cutter mounted on said shaft, a cylindrical edge gauge mounted on said shaft and adjustable longitudinally thereof and surrounding the inner ends of the cutter teeth, a bracket secured to said bearing and projecting over said gauge and cutter, and a guard for the side of the shoe heel comprising a flat bar secured to said bracket and extending therefrom in a plane across the outer end of said cutter with its edge adjacent to the edge of the cutter teeth, the edge of the guard being circular and following the periphery of the cutter.

In testimony whereof I hereunto affix my signature this 18th day of November, 1927.

LEO SCHILDKNECHT.
